AUTOMATIC STOKER

Arthur V. Sampsell, Lafayette, Ind., assignor to
 Sears, Roebuck & Company, Chicago, Ill., a
 corporation of Delaware

Application March 30, 1931, Serial No. 526,502

4 Claims. (Cl. 236—46)

My invention relates to controls for automatic stokers for feeding fuel such as coal, to furnaces. In stokers of this kind it is customary to actuate the stoker by a motor, in the circuit of which there is located a thermostat that is controlled by the temperature of the room to be heated. A difficulty that is encountered in this control is that in mild weather the temperature of the room may remain above that at which the thermostat is set, for a period of time of such duration, that the fire would die out.

An object of my invention is to provide means for periodically actuating the stoker irrespective of the condition of the room thermostat.

Another object of the invention is to provide means regulating the length of time of each periodical actuation of the stoker.

These and other objects are attained by the means described in the specification and illustrated in the drawing in which:

Fig. 1 is a diagrammatic view including the electric power circuit and the controls for opening and closing said circuit through the motor which drives the apparatus;

Fig. 2 is a front view of the time interval or fire-kindler control mechanism with the cover removed; and

Fig. 3 is a side view of said mechanism with the cover shown in dotted lines.

As shown diagrammatically in Fig. 1, a motor 92 has a shaft 101 with a worm 102 which turns a worm wheel 103 with which an eccentric 104 rotates. The eccentric reciprocates a rod 110 guided by the pin-and-slot connection at 115, 116, said rod operating through its arm 110a, a link 120, bell crank lever arms 121 and 122 and pivoted pawl 123 to intermittently rotate a ratchet wheel 124 with which a conveyor worm or screw 69 turns. The conveyor receives fuel from a hopper 60 and feeds it along a conduit 68 to a burner 43. The angle through which the ratchet wheel is moved by the pawl 123 may be governed by a guard 130 connected by an arm 133 and a link 134 to a knob or dial 135 bearing a scale in juxtaposition to a stationary pointer 136. Any other drive may be employed, since the invention concerns the control of the motor.

In accordance with my invention, a conductor 140 leads from a suitable source of electricity to one terminal of the motor. A conductor 141 from such source leads from the other terminal to the motor to a binding post 142 of a time-interval switch, presently to be described, and includes a normally closed thermostatic safety switch 143 adapted to operate, in the event of excessive or

dangerous heat—such as might be due to failure of the room thermostat switch, or the interval contactor switch, to open the motor circuit at the proper time—to automatically open the motor circuit at a point where the other switches cannot complete the motor circuit and energize the motor to feed more fuel to the fire. Conductor 144 leads to another binding post 145 of the time-interval switch. Conductor 146 bridges across conductors 141 and 144 and includes a normally open thermostatically controlled switch 147, of well known construction, adapted to be located at some central point in a building or residence, such as the main hallway, or living room, and to be set or adjusted so as to close when the temperature falls below a certain predetermined degree and to open when the temperature reaches said predetermined degree, the electric motor being operated during the interval to actuate the stoker and feed coal to the fire. A time interval switch is connected in circuit between said terminals 142 and 145, and acts to close the circuit through the motor to feed fuel to the fire at regularly recurring intervals, in the manner presently described, thereby to keep the fire kindled or alive.

Irrespective of the action of the aforesaid thermostatic switch 147, in its control of the operation of the motor to feed fuel to the fire in response to fall of the temperature in the room or space to be heated below the predetermined minimum (say for example 70° F.), the motor circuit is adapted to be closed and the motor thus operated during a predetermined period of time at regularly recurring predetermined intervals of time, to effect what may be termed "fire kindler control", or "time interval control", of the feeding of fuel; that is, the delivery to the fire at fixed time intervals of a small quantity of fuel sufficient to keep the fire kindled or burning, thus insuring the constant maintenance of what may be termed a "pilot fire". This is necessary where there may be a relatively long interval between feedings of fuel to the fire in response to operations of the thermostatic switch 147, with consequent danger of the fire going out between operations. Such danger occurs particularly during periods of mild weather, when the room temperature may not, for a considerable stretch of time, reach the degree required to bring the thermostatic switch 147 into operation.

The fire-kindler control switch mechanism is shown diagrammatically in Fig. 1, but is illustrated more in detail in Figs. 2 and 3. 150 is a base plate of fibrous or other non-conducting ma-

terial, secured in an upright position to a wall or other support near the furnace by screws 151, 151. A removable cover 152, shown in dotted lines in Fig. 3, is secured by screws to the edge of base 150 and encloses the entire mechanism. A plate 153, preferably of brass, is pivoted at its lower end to base plate 150 by a pivot stud 154 (Fig. 3) and at its narrow upper end is freely movable sidewise under a guide bar 155, the latter being secured at its opposite ends to base 150 by screws, but between said ends, where it passes over plate 153, being spaced away from said base. At the upper narrow end of plate 153, a part cut therefrom forms a pointer 156, beyond which said plate extends forward and downward to constitute an overhanging arm 157. The position of pointer 156 in reference to a graduated scale on base 150 indicates the angular position to which plate 153 is adjusted or tilted on its pivot stud 154. To secure plate 153 in the desired angular position, it is engaged by a winged clamp-nut 158 on a fixed screw stud which projects through a curved slot 159 in plate 153, the arc of curvature of said slot being concentric with pivot stud 154. By loosening nut 158 the plate 153 can be turned on its pivot stud 154 a distance limited by slot 159.

160 is a clock mechanism, or the equivalent thereof, secured to the lower end of plate 153 and having a projecting shaft 161, revolving preferably once each hour, and having secured thereto a cam 162 engaged by the lower free end of an arm 163, which is rigidly secured at its upper end to a yoke 164, pivoted by a bolt 165 to the extremity of the arm 157 of plate 153.

166 is a mercury tube switch, of the type of the well known "Mercoid" switch of the American Radiator Co., secured in the yoke or clamp 164, and comprising a sealed glass tube containing a quantity of mercury 167 and two electric terminals 168 and 169, from which terminals conductors lead through the wall of the glass tube to the binding posts 145 and 142, respectively.

Assuming that the cam 162 rotates once an hour, it will be apparent that by its action on arm 163, said cam will tilt the tube to the right and cause the mercury to run to that end of the tube and there electrically connect terminals 168 and 169 in the manner indicated in Fig. 1. Further, it will be apparent that this will occur once each hour, thereby closing the motor circuit between the binding posts 142 and 145 and causing the motor to actuate the fuel feed-screw so long as the mercury remains in said position to connect the tube terminals 168 and 169. But how long the mercury will remain in said position, and consequently the duration of each closing of the motor circuit and its actuation of the fuel-feed screw, is determined by the position in which the plate 153 is held by clamp-nut 158 and may be varied by changing the angular position or tilt of said plate.

The high point of cam 162 passes from under the end of arm 163 at the same instant each hour, and simultaneously therewith the tube tilts to the left and the mercury flows to that end of the tube and opens the circuit at the terminals within the tube. On the other hand, the instant at which the tube is tilted to the right sufficiently to cause the mercury to run to that end of the tube and electrically connect the terminals, may be advanced or retarded according to the position of plate 153.

In practice, the duration of contact is preferably variable from a maximum of say twelve minutes to a minimum of say thirty seconds. The length of slot 159 may be such as to permit of that

or any other desired range of duration. For example, when plate 153 is swung as far to the left as slot 159 permits, contact arm 163 does not tilt the mercury tube 166 sufficiently to cause the mercury therein to close the circuit until the contacting end of said arm has nearly reached the highest point of cam 162 and is about to drop to the lowest point thereof. Hence the closing of the circuit will be of very brief duration, say half a minute. But by swinging the plate 153 to the right, the pivotally supported mercury tube is brought to a position more nearly level, and consequently cam 162 will tilt it into contact-making position a considerable time—say twelve minutes—before the end of arm 163 drops off the highest point of said cam.

If said plate is set to the limit of its adjustment toward the left, the shifting of the mercury to the right-hand end of the tube will be retarded to the limit, and the duration of its closing of the motor circuit correspondingly curtailed to the minimum, say of thirty seconds. Setting of the plate 153 to the limit of its adjustment toward the right will have the reverse effect, and will result in increasing the duration of closing of the motor circuit to the maximum, say of twelve minutes.

The provisions thus made for changing or adjusting the duration, say within a range of one-half a minute to twelve minutes, of each actuation of the fuel conveyor for purposes of kindling the fire, as well as the means whereby such variation may be accomplished, are particularly important features of this invention. Thereby the apparatus is made adaptable to a wide range of variable conditions of use; for example, from conditions under which feeding of coal for one-half minute once each hour may suffice to keep the fire kindled, to conditions under which feeding of the coal for twelve minutes once each hour may be required for that purpose.

The automatic operation of the stoker in response to the two controls, or dual-controls, will be readily understood from the preceding description. The room thermostat switch 147 and the mercury fire-kindler switch 166 are connected in parallel between conductors 141 and 144. If the fire, as kept kindled and burning by the fuel fed thereto periodically by the closing of said mercury switch 166, does not sufficiently heat the room or space in which said thermostatic switch 147 is located, then the latter closes and causes fuel to be fed to the fire until the temperature of the room reaches the predetermined minimum and opens said thermostatic switch. It may happen that while either the switch 147 or the switch 166 is closed, the other will be closed also; and that after one switch has opened its part of the circuit, the other switch will continue to maintain its parallel part of the circuit in a closed condition and thus continue the feeding of fuel to the fire.

The determination of the proper setting of the adjustments of both the transmission gearing and the fire-kindler control switch will of course depend upon the particular conditions applying to each installation, including the kind of furnace, character of fuel, size of house or space to be heated, generally prevailing weather conditions, etc. Furthermore, the adjustment of the fire-kindler control will depend to a considerable extent upon the adjustment of the transmission gearing.

Assuming an installation to be made in a small house, say of five rooms, the first adjustment to

be determined would be that of the ratchet drive of the transmission gearing, which adjustment is effected by turning the knob or dial 135 of Fig. 1. Assuming this adjustment to be set so that each forward movement of the pawl 123 will rotate the ratchet wheel 124 (and with it the fuel feed-screw) a distance of two teeth of said wheel — when the room thermostat switch closes the circuit, the fuel feed-screw is rotated the distance of two teeth of the ratchet-wheel for each forward movement of the pawl, and continues such operation until the room temperature rises to the predetermined minimum and actuates the thermostatic switch to open the circuit. This adjustment should be such that the rotation imparted to the fuel feed-screw will deliver sufficient fuel to the fire to result in increasing the room temperature to the predetermined minimum degree within a reasonable time, say from three 20 minutes for mild weather to fifteen minutes for cold weather.

Assuming an installation using the same coal for a relatively large house, or say twelve rooms, the adjustment would be set to rotate the ratchet wheel (and fuel feed-screw) a larger number of teeth, say five, for each forward movement of the pawl, thus to deliver a correspondingly larger quantity of coal in response to closing of the motor circuit by the room thermostat switch and enable the predetermined degree of temperature to be reached within a reasonable time, say from three minutes for mild weather to fifteen minutes for cold weather.

Assuming similar installations, but using coal having a relatively lower B. t. u. content, if the same adjustments were used as described above, relatively longer periods of operation would be necessary before the room temperature would reach the degree to cause the thermostat switch to open the motor circuit. This time would be shortened by setting the adjustment to rotate the ratchet wheel (and fuel feed-screw) a larger number of teeth on each forward movement of the pawl.

This adjustment only takes into consideration the size of the house to be heated and the character of the fuel being burned and is determined without regard to the adjustment of the fire kindler control next described.

As thus appears, the transmission gearing herein described affords a flexibility of adjustment to meet the particular conditions encountered in making different installations, including different sizes of residences, apartments, or other buildings, and different kinds of fuel.

Coming now to the adjustment of the fire kindler control switch—assume an installation to be made in a small house, say of five rooms, using relatively slow burning coal—the adjustment would be such as to give a relatively long duration, say five minutes, of closing of the motor circuit and operation of the fuel feed-screw once each hour; in other words, a relatively small quantity of the slow burning coal would be delivered once each hour. If the coal used were fast burning the adjustment would be such as to increase said duration of operation of the motor, because as the coal would burn faster more coal would have to be delivered to keep the fire kindled. Using the same kind of fuel, either slow burning or fast burning, a given quantity thereof, sufficient to keep the fire kindled, will serve that purpose, whether the house being heated is large or small. Therefore, when the ratchet mechanism is set to feed more coal for a large

house than for a small house, the adjustment of the fire kindler control must be set accordingly. For example, assume the ratchet mechanism to be adjusted to feed two teeth for each forward stroke of the pawl for a five room house, then for a larger house, say of twelve rooms, with the ratchet mechanism adjusted to feed five teeth for each forward stroke of the pawl, the adjustment of the fire kindler control switch would be such as to shorten the duration of the closing of the motor circuit once each hour. As thus appears, the adjustment of the fire kindler control switch must take into consideration the adjustment of the ratchet mechanism of the transmission gearing.

Differences in flue drafts should also be taken into consideration in setting the adjustment of the duration of the closing of the motor circuit, longer duration, with correspondingly larger amount of coal, being required with a strong stack draft than with a weaker stack draft.

As thus appears, there is a wide range of flexibility of adjustment of the fire kindler control switch, sufficient to efficiently care for practically any and all variations of conditions encountered in making different installations. Furthermore, as clearly appears, the first kindler control switch or mechanism herein described can be adjusted on the job; that is to say, the mechanism as manufactured can be installed in any house or building, and can there be adjusted to meet the particular conditions encountered. It can also be shifted from one installation to another and adjusted to the particular conditions of the new installation.

What is claimed is:

1. In combination, a furnace, a mechanical stoker, a single control circuit controlling the operation of the stoker, a furnace thermostat and a room thermostat in series with the control circuit, and a time switch connected in multiple solely with the room thermostat.

2. In combination, a furnace, a motor operated stoker, time control means for periodically closing the motor circuit, a furnace thermostat and a room thermostat operable to close the motor circuit independently of the time control means, said time control means being adapted to close and open the motor circuit when the furnace thermostat is in circuit closing position and the room thermostat is in circuit opening position.

3. In combination, a furnace, a motor operated stoker, time control means for periodically closing the motor circuit, a furnace thermostat and a room thermostat operable to close the motor circuit independently of the time control means, said time control means being adapted to close and open the motor circuit when the furnace thermostat is in circuit closing position and the room thermostat is in circuit opening position, together with means associated with said time control means for varying the duration of closure of the motor circuit independently of periodicity.

4. In combination, a furnace, a motor driven stoker, a single control circuit for starting and stopping the motor, a furnace switch responsive to temperature conditions in the furnace, a room switch responsive to temperature conditions in a room to be heated, said furnace and room switches being connected in series in said control circuit, and a time switch connected in multiple with said room switch and in series with said furnace switch.

CERTIFICATE OF CORRECTION.

Patent No. 2,164,350.
